DOOR LOCK

John H. Reethel, Detroit, Mich., assignor to
 Reethel Engineering Corporation, Detroit,
 Mich., a corporation of Michigan

Application August 18, 1944, Serial No. 550,036

3 Claims. (Cl. 292—229)

1

This invention relates to latch mechanism for swinging doors. Although the invention is applicable to various types of door structures, it is especially useful in connection with latch mechanism adapted for use in connection with doors of automobiles and other vehicles and contemplates the provision of improved mechanism which combines in relatively simple form such desired features as simplicity in construction, operational efficiency and mechanical practicability.

An object, therefore, of the invention is to provide an improved mechanism of the above class or type which is relatively simple and compact in construction, economical to manufacture, easily operated, durable and efficient in use, and which in operation is capable of providing an easy and relatively quiet closing door.

In accordance with the embodiment of the invention, herein illustrated by way of example, there is provided a rotatable plate having a latch bolt projecting therefrom at a point offset from the axis of rotation of the plate. There is also provided a lever fulcrumed intermediate its ends, which lever has an operative connection with a shiftable detent. The detent is adapted to lock the rotatable plate in a latching position of the bolt. The fulcrumed lever is engageable at each end thereof by manually operable means for selectively swinging the lever to shift the detent to release the plate.

A specific feature of construction is that the connection between the lever and the detent lies between one end of the lever and the fulcrum thereof. Another specific feature of construction is that a single resilient means is provided for urging the lever and detent into plate locking position and also for urging said bolt toward bolt unlatching position.

Other objects of this invention will appear in the following description and appended claims, reference being had to the accompanying drawings forming a part of this specification wherein like reference characters designate corresponding parts in the several views.

Fig. 1 is a fragmentary perspective view of the inside of an automobile body provided with swinging doors upon which latch devices in accordance with the present invention are installed.

Fig. 2 is an enlarged horizontal section taken substantially through lines 2—2 of Fig. 1 looking in the direction of the arrows.

Fig. 3 is a vertical section taken substantially through lines 3—3 of Fig. 2 looking in the direction of the arrows.

2

Fig. 4 is a vertical section taken substantially through lines 4—4 of Fig. 2 looking in the direction of the arrows.

Fig. 5 is a view in elevation taken substantially from lines 5—5 of Fig. 2 looking in the direction of the arrows.

Fig. 6 is a view similar to Fig. 3 but illustrating the mechanism in unlatched position.

Fig. 7 is a vertical section taken substantially through lines 7—7 of Fig. 4 looking in the direction of the arrows and showing the bolt in latched position with respect to the striker member.

Figs. 8 and 9 are views somewhat similar to Fig. 7 but illustrating, respectively, unlatched and safety positions of the bolt with respect to the striker member.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

In the drawings there is illustrated, by way of example, one embodiment of the present invention as applied to a door and door frame structure, such as that of an automobile body. As illustrated in Fig. 1, the automobile body is designated generally at A and is provided with front and rear doors B and C, respectively. Each swinging door is hinged at one edge so as to swing against a common door post or body pillar 30 in accordance with conventional practice and comprises an outer metal door panel 10 and an inner metal door panel 11. The panel 11 terminates in a transverse jamb edge or portion 12 facing the fixed jamb face or edge 13 of the door frame post or body pillar 14.

The latch device embodying the present invention is shown in detail as applied to the front door B of the automobile and comprises a case plate 15 engaging the inner surface of the inner door panel 11 and provided with a transversely extending flange 16 adapted to fit against the inner surface of the jamb edge 12 of the door. The case plate is rigidly secured in suitable manner, such as by screws, to the door panel portions 11 and 12. Mounted against the inner face of the case plate flange 16 is a bolt carrying plate or member 17 which is rotatable upon a pivot or stud 18 in the form of a shoulder rivet set 50 cured to the case plate flange 16. Rigidly se-

3

cured to the plate member 17 at a point spaced from the pivotal axis 18 of the plate is a cylindrical latch bolt 19. This bolt is thus carried by the plate 17 eccentrically and projects outwardly through an arcuate slot 20 in the case plate flange 16 and also an arcuate slot 21 in the jamb face 12 of the door, the slots 20 and 21 registering one with the other. The bolt carrying plate 17 is formed on its periphery at points above the pivot 18 with inclined abutments or shoulders 22 and 23, the shoulder 22 representing the safety locking position of the bolt and the shoulder 23 representing the final locking position thereof. At a point spaced in a counter-clockwise direction from the shoulder 23 is a third abutment or shoulder 24 adapted, as later described, to provide in part additional means for locking the plate 17 in the final locking position of the bolt.

Associated with the bolt carrying plate or ratchet member 17 is a detent or pawl 25 which is pivoted to swing up and down upon a pivot stud or shoulder rivet 26 secured to the case plate flange 16. It will be noted that the plate 17, as viewed from Figs. 3 and 6, is rotatable in a clockwise direction when the bolt moves from the unlatched position shown in Fig. 6 to the latched position shown in Fig. 3. The detent 25 is, therefore, pivoted at 26 adjacent the inner side of the door and is provided with a dog or detent portion 25a provided with an inclined contacting face or edge engageable successively with the shoulders 22 and 23 when the door is closed. The detent portion 25a by virtue of the clockwise movement of the bolt carrying plate locks the plate against counter-clockwise movement when in engagement with either of the shoulders 22 or 23.

The detent 25 is activated for the purpose of swinging it out of locking position with respect to the plate 17 by means of a swinging operating lever 27. This lever is mounted to turn or rotate upon a pivot stud or shoulder rivet 28 secured to the case plate. The upper arm of the lever extends in a generally horizontal direction toward the inner side of the door and at an intermediate point on this upper arm portion a headed pin 29, rigidly secured to the outer end of the detent 25, projects through a horizontal slot 30 in the lever. Thus, the pin and slot connection 29 and 30 provides an articulated connection between the lever and the detent and, hence, it will be seen that by raising or swinging upwardly the upper arm portion of the lever 27 the outer end of the detent will be lifted, thereby withdrawing the detent portion 25a from engagement with the shoulder 22 or the shoulder 23. Thus, by swinging the lever 27 about its fulcrum 28 a short distance in a clockwise direction the detent 25 will be swung in the opposite direction about its pivot 26 by reason of the pin and slot connection 29 and 30 thereby releasing the plate 17.

The bolt carrying plate 17 is constantly urged toward the position shown in Fig. 6, namely, the unlatching position of the door latch when the door is open, by means of a tension spring 31. This spring not only tends at all times to impart counter-clockwise rotative movement to the plate 17 but at the same time exerts an effort to swing the lever 27 about its fulcrum thereby urging the detent 25 toward the plate 17. Accordingly, the spring 31 is connected at its lower end to a pin 33 secured to the plate 17 at a point outwardly of the pivot 18. The upper end of the spring 31

4

is connected to a pin 32 secured to the lever 27 at a point inwardly of the fulcrum 28 of the lever. The connection 32 of the spring with the lever may be relatively close to the fulcrum 28 in order to reduce, as desired, the leverage action exerted by the spring to hold the lever and detent down toward the plate 17. The position of the spring 31 when the door is unlatched is shown in Fig. 6 and it will be seen that the downward pull on the lever and detent exerted by the spring in this position of the latch bolt is relatively light. However, as the plate 17 is rotated from the position of Fig. 6 toward the position of Fig. 3, the tension of the spring progressively increases and, hence, in the final locking position of the bolt, as shown in Fig. 3, considerable effort is exerted by the spring to hold the detent in locking position against the final locking shoulder 23. By virtue of the foregoing construction it will, therefore, be seen that a single spring means, anchored at 33 to the bolt carrying plate and at 32 to the detent operating lever, may be utilized to return the plate 17 and the bolt 19 to unlatching position and also to hold the detent down against the periphery of the plate 17 while at the same time the detent 25 is held down against the periphery of the plate 17 under progressively increasing pressure as the bolt and plate move toward latching position.

The detent operating lever 27 has a depending extension or crank arm 34 offset longitudinally at its lower end to provide an enlarged or widened portion 34a disposed for engagement by a push button plunger 35 manually operable from the outside of the door. The plunger is urged into retracted position by a compression spring 36 housed within a recess 37 in an outside fixed door handle 38. By pushing the plunger 35 inwardly against the action of the spring 36 in the direction of the arrow in Fig. 3, the arm extension 34 of the lever 27 will be swung inwardly thereby raising the opposite end of the lever and withdrawing the detent 25 from engagement with the locking shoulder 23 or 22.

Pivoted to the case plate 15 at the inner side of the door is a bell crank lever 39, the lever being rotatable upon a stud or shoulder rivet 40. The lower arm 39a of this lever is offset transversely at 39b (Fig. 2) and this offset portion terminates in an outwardly projecting actuating finger 39c extending beneath a portion 27a on the end of the lever 27, this portion being formed by embossing the metal of the lever at its upper terminal end inwardly to increase its bearing 55 contact with the finger 39c. The upwardly extending arm 39b of the lever 39 carries a pin 41 extending through a longitudinal slot 42 in one end of a remote control link 43. The opposite end of the link 43 is pivotally connected by 60 means of a pin 44 to a bell crank lever 45 which extends between and is pivoted at 46 to the bifurcated ends 47a of an adjustable mounting plate or bracket 47 secured to the inner metal door panel 11 by means of screws 48 extending through adjusting slots 49 in the bracket, see Fig. 5. The lever 45 has an actuating arm 45a extending through an aperture in the panel 11 for engagement by an inside push button plunger 460 which projects through a hole 470 in the outer trim panel 149 secured to the metal panel 11. The plunger 460 is secured to a push button 52 extending through a hole in a fixed inner door handle 51, inward movement of the plunger being resisted by a compression spring 499 housed 65 within a recess 50 in the door handle. From this

construction it will be seen that by pressing the push button 52 inwardly the lever 45 will be rotated about its pivot 46 thereby retracting the link 43 and rotating the lever 39 about its pivot 40 causing the finger 39c of the lever to raise the inner end 27a of lever 27 and withdrawing the detent 25 from engaging position with the locking shoulder 23 or 22.

In accordance with the present invention additional means is provided for locking the bolt carrying plate 17 in the position shown in Fig. 3 when this plate as well as the latch bolt 19 has been moved to the final locking position. This additional locking means for the plate 17 comprises a locking lever 53 having an inwardly offset portion 53a pivoted at its lower end at 54 to the case plate 15. The lever is embossed outwardly at 53b to provide a channel portion having an upper wedge shaped or tapering contacting face 53c adapted to engage beneath the locking shoulder 24 on the plate 17, as shown in Figs. 3 and 4. The lever 53 is guided in its swinging motion about its fulcrum 54 by means of an arcuate slot 55 in the lever through which extends a guide pin 56 secured to the case plate. Pivoted at 57 to the inner end of the lever 53 is a vertically extending rod or plunger 58 adapted to project through the garnish molding at the lower edge of the window opening and carrying a knob or button 59 at its upper end, as shown in Fig. 1. The knob 59 is accessible at the inner side of the window glass of the door and when pushed down will shift the plunger 58 downwardly to swing the lever 53 in the direction of the arrow shown in Fig. 4 thereby swinging the locking projection 53b of the lever out from beneath the locking shoulder 24 thereby releasing the plate 17. Upward movement of the plunger 58 will swing the lever 53 in the reverse direction thereby shifting the locking or detent portion 53b of the lever into position beneath the shoulder 24, thus locking the plate 17 against rotative movement toward unlatched position of the bolt. The inclined contacting face 53c of the detent portion 53b will produce a wedging engagement with the face of the shoulder 24, thus causing the detent portion 53b to engage the locking shoulder firmly and also providing a take-up to compensate for wear or variations due to allowable tolerances in production. It is important to note from this construction that the locking lever 53 with its detent portion 53b, which cooperates with the locking shoulder 24 on plate 17, is operated entirely independently of the detent 25 and will be effective to hold the plate 17 and latch bolt in the fully latched position thereof irrespective of operation of either the outside push button plunger 35 or the inside push button plunger 48 to release the detent 25 by operation of the lever 27. Hence, with the inside locking lever 53 in its locking position shown in Figs. 3 and 4 either the inside or the outside push button may be freely pressed to shift the detent 25 upwardly away from locking engagement with the shoulder 23 without unlocking the door. The locking lever 53 has the additional advantage of providing in conjunction with the detent 25 two separate means for locking the latch bolt in its final locking position thus insuring greater safety during operation of the vehicle.

From the foregoing it will be seen that the latch bolt 19 is movable between unlatching and latching positions in an arcuate path as defined by the arcuate slots 20 and 21. The bolt is actuated when the door is closed by means of a striker

member which is preferably mounted upon the jamb edge 13 of the pillar or fixed upright member of the door frame. In the present instance the striker comprises a pressed metal plate 60 which is stamped into a hollow generally rectangular member adapted to be secured to the door frame by screws 61. The striker plate is formed with a curved slot 62 open at its lower end and extending inwardly and upwardly as shown in Figs. 7 to 9 inclusive. The upper end of the slot 62 is closed and also shaped to conform substantially to the shape of the bolt 19. Projecting into the upper end of the slot 62 of the striker member is a resilient rubber bumper 63 which is housed within a recess 64 in the striker plate and secured therein by one of the screws 61. The lower face of the bumper 63 is lined or covered by means of a spring steel liner member 65. This member is in the form of a spring having its opposite ends anchored within notches in the bumper 63. The spring liner 65 provides a metal wear resisting surface between the rubber bumper and the bolt while enabling the bolt to compress the bumper somewhat when the bolt is forced through the slot 62 into the upper end thereof. It will be noted that the upper end of the slot 62 has a generally vertically extending wall 62a engaged by the bolt and which positively prevents outward movement of the bolt when in its final locking position as shown in Fig. 7. Secured to the jamb edge of the door is a wedge member 66 which is adapted to engage and ride over the upper inclined or wedge face 60a of the striker plate 60 during closing movement of the door. The co-operation of these wedge parts insures proper closing movement of the door to cause the bolt to enter properly the lower end of the slot 62 and also provides a positive means for holding the door against downward movement as a result of vibrations incident to operation of the vehicle. Coaction between the bolt and the resilient rubber bumper 63 resists upward movement of the door resulting from vibrations consequent to operation of the vehicle. Thus, when the door is fully closed it is held relatively firmly against vertical vibrational motion by engagement of the wedge member 66 with the upper inclined surface 60a of the striker plate and by engagement of the bolt 19 with the bumper 63. The spring liner 65 covers the entire lower surface of the rubber bumper 63 and, hence, transmits the force of impact of the bolt throughout the cross-section of the bumper.

It will be noted that the surface of the plate 17 contacts smoothly the inner surface of the case plate flange 16 and is constructed so as to provide a portion which will entirely cover and close the slot 20 in the case plate when the bolt is in unlatched position as shown in Fig. 6. Hence, when the door is open there will be no undesirable open slot through the jamb edge of the door exposing the inside of the latch device since the plate 17 at this time will effectually close the slots 20 and 21. It will also be noted that the reverse slots 62 and 21 (see Figs. 7 to 9) through which the bolt travels produce what may be termed a scissors locking action and, hence, a very efficient means for holding the bolt in latching position.

Although the manually operated means for releasing the detent 25 are herein shown in the form of inside and outside push buttons, it will be understood that conventional turning handles may be substituted for actuating the lever 27. In such case it will be noted that when the door is locked by the lever 53 both handles would be

free to turn since any operation of the lever accompanied by release of the detent cannot effect unlatching of the door until the lever 53 has been shifted to release its detent portion 53b from locking engagement with shoulder 24. Where it is desired to use a key operated lock on one or more of the doors it will be understood that the lock cylinder which receives the key may be installed in a hole in the push button plunger 35, suitable means being operated upon turning the key to lock the plunger against inward movement.

I claim:

1. In a door latch, a rotatable plate having a latch bolt projecting therefrom at a point offset from the axis of rotation of the plate, a lever fulcrumed intermediate its ends, a shiftable detent adapted to lock said plate in a latching position of the bolt, an operative connection between the lever and detent, and manually operable means engageable with each end of the lever for selectively swinging the same to shift the detent to release said plate.

2. In a door latch, a rotatable plate having a latch bolt projecting therefrom at a point offset from the axis of rotation of the plate, a lever fulcrumed intermediate its ends, a shiftable detent adapted to lock said plate in a latching position of the bolt, an operative connection between the lever and detent, and manually operable means engageable with each end of the lever for selectively swinging the same to shift the detent to release said plate, said connection lying between one end of the lever and the fulcrum thereof.

3. In a door latch, a rotatable plate having a latch bolt projecting therefrom at a point offset from the axis of rotation of the plate, a lever ful-

crumed intermediate its ends, a shiftable detent adapted to lock said plate in a latching position of the bolt, an operative connection between the lever and detent, manually operable means engageable with each end of the lever for selectively swinging the same to shift the detent to release said plate, and a single resilient means for urging said lever and detent into plate locking position and also for urging said plate toward bolt unlatching position.

JOHN H. ROETHEL.
